INVENTOR.

UNITED STATES PATENT OFFICE.

ARTHUR MIDDLETON ROSE, OF YONKERS, NEW YORK, ASSIGNOR TO
MATTHEW J. WHITTALL, OF WORCESTER, MASSACHUSETTS.

DESIGN FOR CARPET.

SPECIFICATION forming part of Design No. 25,541, dated May 19, 1896.

Application filed April 16, 1896. Serial No. 587,868. Term of patent 31 years.

To all whom it may concern:

Be it known that I, ARTHUR MIDDLETON ROSE, a citizen of the United States, residing at Yonkers, in the county of Westchester and State of New York, have invented and produced a new and original Design to be wrought into Wilton and other Carpeting in such coloring as may be designed, of which the following is a specification.

This invention comprises two parts—namely, the design A for a carpet-body, and the design B for a border; and I do hereby declare that the drawing accompanying this specification gives and conveys to any one skilled in the art of carpet weaving and manufacture a clear understanding of same, and is sufficient to enable such person to use my invention.

The body A shows clusters of flowers of the chrysanthemum type appearing on a watered background.

The border B shows a continuous vine of the flowers, as in body, on similar groundwork, together with an ornamental outer edge.

What I claim as my invention, and desire to secure by Letters Patent, is—

1. In a design for a carpet, the body A, substantially as shown.
2. In a design for a carpet, the border B, substantially as shown.
3. The design for carpets, consisting of the body A and the border B, substantially as shown.

In testimony whereof I have hereunto set my hand in the presence of two subscribing witnesses.

ARTHUR MIDDLETON ROSE.

Witnesses:

W. H. JUDSON,
N. A. McMANUS.
